SAW ATTACHMENT FOR A ROTARY DRILL

Jonas Theodore Lindquist, Skokie, Ill., assignor, by mesne assignments, to Thor Power Tool Company, Aurora, Ill., a corporation of Delaware

Application April 27, 1955, Serial No. 35,708

Term of patent 3½ years

(Cl. D90—3)

Fig. 1 is a perspective view of a saw attachment for a rotary drill, showing my new design;

Fig. 2 is an end view of the same as viewed from line 2—2 of Fig. 1; and

Fig. 3 is a front view of the same as viewed from line 3—3 of Fig. 1.

The drill and feed cable shown in phantom lines in Fig. 1 are disclosed only for purposes of illustration.

I claim:

The ornamental design for a saw attachment for a rotary drill, as shown and described.
